UNITED STATES PATENT OFFICE.

ALFRED RAYMOND AND ALBERT RAYMOND, OF WASHINGTON, DISTRICT OF COLUMBIA.

INNER TUBES FOR PNEUMATIC TIRES.

1,078,515.

Specification of Letters Patent. Patented Nov. 11, 1913.

Application filed September 25, 1913. Serial No. 791,829.

To all whom it may concern:

Be it known that we, ALFRED RAYMOND and ALBERT RAYMOND, citizens of the United States, residing at Washington, District of Columbia, have invented and discovered certain new and useful Improvements in Inner Tubes for Pneumatic Tires, of which the following is a specification.

Our said invention consists in certain improvements in the form and arrangement of inner tube structures for pneumatic tires for vehicle wheels of that type comprising multiple chambers or tubes adapted for successive use, whereby when one chamber becomes punctured or disabled, another may be quickly and conveniently inflated and adapted to take its place in the tire without the trouble, delay and expense of removing one tube and substituting another.

This invention is a further development of the invention forming the subject matter of our Patent No. 1,065,836 of June 24, 1913, and embodies the same advantages set forth for the particular structure disclosed in said patent with the additional advantages of more complete and perfect union of the individual tubes constituting the several chambers, and an arrangement more convenient to make and to use, all as will be hereinafter more fully described and claimed.

Referring to the accompanying drawings, which is made a part hereof, and on which similar reference characters indicate similar parts, Figure 1 is a cross-section through an inner tube structure for pneumatic tires embodying our said invention, Fig. 2 a similar view showing one of the side chambers (illustrated as collapsed in Fig. 1) inflated, Fig. 3 a detail section on an enlarged scale illustrating the air valve mechanism, Fig. 4 a perspective view of parts of said valve separate, Fig. 5 an underside plan view of the controlling valve, and Fig. 6 a section on the dotted line 6—6 in Fig. 3.

In said drawings the portions marked A, B, and C represent the respective tubes of which the complete inner tube structure is composed. Said tube structure comprises the outer tube A which surrounds the entire inner tube structure and the tubes B and C which respectively constitute about one third of the interior circumference of the structure, and are united at their inner contiguous edges, as at point y, and are also united for a distance substantially equal to

their diameters, with the inner surface of the tube A. Between the outer edges of the tubes B and C, as at the points x and z, the outer tube A is formed with a thickened portion a of substantially the thickness of the double walls of said tubes B and C, and adjacent to the tread of the tire.

The valve structure comprises a casing 10 having a tubular outer end and a solid inner end with a base plate 11 which is inserted in an aperture through the tube A and lies between said tube and the edges of the tubes B and C, being clamped in position by a screw-threaded clamping washer 60 or nut 12. A hollow valve stem 13 is mounted in the casing 10, the lower end of said stem being closed except for a single perforation 14 and its outer surface is provided with a disk of rubber or other packing material 15. The solid lower end of casing 10 is provided with three separate ports or channels 16, 17, and 18, respectively, port 16 leading directly into the chamber within tube A, port 17 leading to 65 one side and connected to discharge within tube B, and port 18 leading to the other side and connected to discharge within tube C, as clearly illustrated in Fig. 3.

The upper end of casing 10 is provided 70 with three slots; 19, 20, and 21, and the tubular stem 13 is provided with a lug 22 and an indicator mark, as an arrow 23, pointing therefrom. When said stem is turned so that the lug 22 registers with slot 19 the aperture 14 will register with the appropriate one of the ports 16, 17, or 18. When the lug registers with slot 20, communication will be established with another port, and when it registers with slot 21 75 communication will be established through the other port. In this manner either tube A, B, or C may be inflated at the will of the user and by inflating them in successive order the position of the lug 22 in relation to the several slots which are indicated by numerals, or in any other appropriate manner, in successive order, will indicate what tubes have been used and which tube should be used next.

In use the inner tube structure is arranged first as shown in Fig. 1 and the air is pumped into tube A which inflates said tube and flattens the tubes B and C against the interior surface of said tube A. In Fig. 1 these tubes are shown with their walls slightly separated, but it will be understood that

2

this showing is merely for the purpose of illustrating that they are in themselves complete tube structures, first made separately from the tube A, or original independent tubes, and to further make clear the separate character of the chambers formed by these tubes. That portion of the outer surface of tubes B and C which lies against the inner surface of tube A when collapsed, as from *x* to *y* and from *y* to *z*, respectively, is fused with said tube A by a process forming the subject matter of our application No. 791,830 filed herewith. The thickened portion *a* of the tube A affords to the tread of the tire the additional thickness and resisting qualities required. When tube A is flattened, or otherwise disabled, the valve 13 is adjusted to direct the air to the tube B, which is then inflated, and after tube B is inflated then the air is likewise directed into the tube C, which is then inflated, the tubes B and C when inflated assuming a position, respectively, such as illustrated in Fig. 2. By an examination of said figure it will be noted that the strain of expansion consequent upon the inflation of either of said tubes B or C will be directed around the circumference of the respective tubes and draws smoothly upon all parts of the walls thereof, and that the walls of the collapsed tube are held straight and smooth underneath the expanded tube, thus avoiding any bunches or wrinkles therein which would materially impair the resiliency of the material, if allowed to remain therein for any considerable continuous period.

By this structure a tire is provided, as in our former patent above referred to, wherein three chambers are available for successive use and the ordinary life of the tire thus trebled.

It will also be noted that in our present structure, as well as in that of our former patent, the individual tubes, or chambers, are arranged in the order of a triangle, whereby it is rendered impossible by a puncture extending entirely through the tire to the rim of the wheel to penetrate the walls of all of said tubes or chambers.

Having thus fully described our said invention, what we claim as new and desire to secure by Letters Patent is:

1. An inner tube for pneumatic tires comprising a series of air chambers, some of

which are contained within the wall surrounding the other chamber, the inner chambers being complete tubes secured to the inner wall of the outer chamber for substantially one half of their circumferences, and an air supply means adapted to discharge into each of said chambers successively, substantially as set forth. 60

2. A multiple chamber inner tube structure for pneumatic tires comprising a series of tubes adapted for successive use, one tube surrounding the other tubes, and the inner tubes secured to the walls of the surrounding tube for a distance approximately equal to their respective diameters, substantially 70 as set forth.

3. A multiple chamber inner tube structure for pneumatic tires comprising a series of tubes one of which surrounds the others, the inner tubes being secured edge to edge 75 and with that portion of their faces adjacent to the outer tube secured to the inner face thereof, said outer tube being formed with a thickened portion in the space between the edges of the inner tubes adjacent 80 to the tread of the tire, substantially as set forth.

4. An inner tube structure for pneumatic tires comprising a series of tubes one of which surrounds the others, said outside 85 tube having a thickened portion and its inner walls having a series of tubes attached thereto edge to edge between the edges of said thickened portion, and means for inflating said tubes successively, substantially as 90 set forth.

5. An inner tube structure for pneumatic tires comprising a series of tubes contained within a surrounding tube and attached to the inner wall of said surrounding tube, 95 said surrounding tube being provided with thickened portions between the adjacent edges of said inner tubes, and means for inflating said several tubes successively, substantially as set forth. 100

In witness whereof, we have hereunto set our hands and seals at Akron, Ohio this 24th day of September, A. D., nineteen hundred and thirteen.

ALFRED RAYMOND. [L. s.]
